UNITED STATES PATENT OFFICE.

GEORGE SABINI, OF NEW YORK, N. Y.

WINDOW.

1,169,054.

Specification of Letters Patent. Patented Jan. 18, 1916.

Application filed May 5, 1915. Serial No. 25,890.

To all whom it may concern:

Be it known that I, GEORGE SABINI, a citizen of the United States, and residing at New York, in the county of New York and State of New York, have invented certain new and useful Improvements in Windows, of which the following is a specification, such as will enable those skilled in the art to which it appertains to make and use the same.

This invention relates to house windows, and the object thereof is to provide a window of this class in which the sashes both top and bottom are counter-balanced, and may be vertically moved and vertically adjusted in the usual manner for ventilation and other purposes, and may also be moved forwardly or inwardly and swung into different positions to facilitate the cleaning of the sashes, or the transparent panels therein, and with these and other objects in view the invention consists in the construction, combination and arrangement of parts hereinafter described and claimed.

The invention is fully disclosed in the following specification, of which the accompanying drawings form a part, in which the separate parts of my improvement are designated by suitable reference characters in each of the views, and in which:

Figure 1 is a vertical section of a window made according to my invention, said section being on the line 1—1 of Fig. 4; Fig. 2 a detail view of a sash attachment which I employ and one of which is connected with the opposite sides of both sashes; Fig. 3 a view of the attachment shown in Fig. 2 but looking in the direction of the arrow 3; Fig. 4 a cross section on the line 4—4 of Fig. 5; Fig. 5 a vertical section on the line 5—5 of Fig. 4; Fig. 6 a section on the line 6—6 of Fig. 5; and, Fig. 7 a section on the line 7—7 of Fig. 6.

In the drawing forming part of this specification, I have shown a window frame, comprising the usual top member *a*, bottom member *a*² and opposite side members *a*³, and the side members *a*³ are made box-shaped in form and contain vertical chambers *a*⁴ in which the counter-balance weights and chains operate, and the said opposite side members *a*³ of the frame are provided with the usual central bead strips *a*⁵ and inner and outer bead strips *a*⁶ and *a*⁷ forming vertical spaces in which the top sash *b* and bottom sash *c* are vertically movable in

the usual manner, and the said chambers *a*⁴ are provided with inner walls *a*⁸. The top sash *b* is provided with side members *b*², a top member *b*³ and a bottom member *b*⁴, and the bottom sash *c* is provided with side members *c*², a top member *c*³ and a bottom member *c*⁴. The opposite sides of the sashes are provided respectively with side supplemental stiles *b*⁵ and *c*⁵ which are of the same vertical height as the sashes, and which are connected therewith and moved vertically therewith in the operation of moving said sashes up and down in the usual way, and the supplemental stiles *b*⁵ and *c*⁵ are provided with tongues *b*⁶ and *c*⁶ which operate in corresponding grooves in the inner and outer bead strips *a*⁶ and *a*⁷ and in the central bead strips *a*⁵.

The sides *b*² and *c*² of the sashes are grooves as shown at *d* to form corresponding tongues *d*², and the supplemental stiles *b*⁵ and *c*⁵ are similarly grooved to receive the tongues *d*², and said sides of the sashes and said supplemental stiles are thus adapted to interlock as shown in Figs. 4 and 6. The supplemental stiles *b*⁵ and *c*⁵ at the opposite sides of the sashes are connected with the bottom portions of said sashes, as shown in Figs. 5, 6 and 7, and in making this connection box members *e* are countersunk and secured in the bottom of the sides of the sashes and to the bottom rails of said sashes, as shown in Figs. 5, 6 and 7, and other box members *f* are secured to, or in the lower ends of the supplemental stiles *b*⁵ and *c*⁵, and the box members *f* are provided in one side thereof with curved slots *f*², and bolts *g* are passed into the box members *e* and *f*, as clearly shown in Figs. 5, 6 and 7, and said bolts *g* are provided with pins *g*² which operate in the slots *f*², and the bolts *g* are locked in the box members *e* by set screws *g*³, and the object of the slots *f*² and pins *g*² is to force the supplemental stiles *b*⁵ and *c*⁵ outwardly, or in the direction of the sides of the window frame when the sashes are manipulated as hereinafter described, and it must be borne in mind that the above described construction, shown in Figs. 5, 6 and 7, in connection with the bottom of the window frame and the bottom of the bottom sash is also employed in connection with the bottom of the top sash and the opposite sides of the window frame.

The top and bottom sashes *b* and *c* are counter-balanced by weights *h* having chains

h^2 passed over pulleys h^3 in the top of the frame and secured to the tops of the sashes in the usual or any preferred manner, and mounted adjacent to the pulleys h^3 at the 5 opposite sides of the window frame are other pulleys h^4 , and movable in the sides of the window frame or in the chambers a^4 are other counter-balance weights h^5 , having chains h^6 which pass over the pulleys h^4 .

10 The supplemental stiles b^5 and c^5 at the opposite sides of both sashes are provided with longitudinal recesses i closed by plates j which are secured to and in said supplemental stiles by screws j^2 , and the lower ends 15 of these plates have countersunk housings j^3 in which are mounted pulleys j^4 , and said plates are provided on the inner sides of the lower end portions thereof with guide pulleys j^5 and the upper end portions of 20 said plates are provided with inwardly set guide pulleys j^6 and j^7 , and the chains h^6 after passing around the pulleys h^4 at the top of the window frame are passed down and around the pulleys j^4 , and then up and 25 around the outer side faces of the pulleys j^5 , and then up and around the inner side faces of the pulleys j^6 , and then around the pulleys j^7 . It will be noted 30 that the pulleys j^7 are set in planes at right angles to the pulleys j^6 as are also the pulleys j^4 , and that the pulleys j^5 and j^6 are in the same plane, and the said chains h^6 after being passed around the pulleys j^7 are secured to the sides of the sashes as 35 shown at j^8 in Fig. 4. The chains h^6 after being passed around the pulleys h^4 are passed down through grooves k in the inner parts b^6 of the supplemental stiles b^5 of the top sash and the outer parts c^6 of the 40 supplemental stiles c^5 of the bottom sash to the pulleys j^4 , this construction being shown in Figs. 4 and 5.

In Fig. 1 of the accompanying drawing, both sashes are shown in dotted lines, as 45 swung inwardly at an angle of from thirty-five to forty-five degrees, and the bottom sash in this position is above the top sash, or said top sash has been lowered and the bottom sash raised, and when the sashes are 50 in this position they may be swung inwardly to any desired angle to facilitate the washing or cleaning thereof, or the transparent panels therein, and the bottom sash may be raised independently of the top sash and 55 swung inwardly, as above described, but in order to swing the top sash inwardly it must be lowered into its lowest position, and the bottom sash turned inwardly and raised above the top of the top sash, after 60 which said top sash may be swung inwardly. It will also be apparent that the bottom sash may be raised slightly and swung inwardly after which the top sash may be lowered slightly and swung inwardly, this 65 position being not indicated.

In the transverse section shown in Fig. 4, the lower sash is shown slightly in perspective or as swung inwardly slightly, while the top sash is shown in its closed position, and when the sashes are both in their normal 70 position, or the position indicated in full lines in Fig. 1, they may be raised and lowered in the usual manner, and in this operation the supplemental stiles b^5 and c^5 move therewith.

75 It will be understood, of course, that the bolts g form pivots on which the sashes turn in the above described operation, and in the operation of swinging the sashes inwardly the pins g^2 travel in the curved slots 80 or grooves g^2 in the box members f which are secured to the supplemental stiles b^5 and c^5 , and this holds the supplemental stiles b^5 and c^5 in close contact with the side members a^8 of the window frame, and this 85 prevents any rattling or shaking of the sashes in the inclined position thereof, or when said sashes are swung inwardly and then back into position, and in the manipulation of the sashes, as hereinbefore described, the counter-balance weights h^5 serve to hold said sashes in any position into 90 which they may be turned, one of said positions being indicated in Fig. 1. My improvement is also not solely designed for 95 the purpose of cleaning windows but, as will be understood, it also facilitates the ventilation of buildings, or rooms, or compartments, for the reason that the sashes may be swung into such positions as will 100 control the currents of air passing through the window, and while I have shown and described the pivotal connection of the supplemental stiles b^5 and c^5 at the bottom of the sashes it will be understood that this 105 exact location of said pivotal connection is not essential, and although I have shown and described the construction which I prefer in order to carry my invention into effect, my said invention is not limited to 110 the exact details of construction herein shown and described, and various changes therein and modifications thereof may be made, within the scope of the appended claims, without departing from the spirit 115 of my invention or sacrificing its advantages.

Having fully described my invention, what I claim as new and desire to secure by Letters Patent, is:—

120 1. A window provided with a counter-balanced sash having a supplemental counter-balanced stile movable vertically with said sash and between the bead strips, said supplemental stile being pivoted to said sash and a supplemental counter-balance 125 weight having a flexible member which is passed around a pulley at the top of the window frame and carried down and passed around a guide pulley arranged at right angles to the sash and then up and around 130

a guide pulley arranged in the plane of said sash and then over and around a guide pulley arranged at right angles to the sash and secured to said sash, said guide pulleys being secured in the supplemental stile whereby the sash may be moved vertically and swung in a plane at right angles to the plane of the window and held at any desired angle to the window frame.

10 2. In an apparatus of the class described, an attachment for the opposite sides of window sashes comprising a plate having a pulley counter-sunk in the lower outer side thereof and in a plane parallel therewith, another pulley mounted on the inner side

thereof above the last named pulley and at right angles to the plane thereof, another pulley mounted above the last named pulley and in the same plane therewith, and another pulley mounted above the last 20 named pulley and in a plane at right angles thereto.

In testimony that I claim the foregoing as my invention I have signed my name in presence of the subscribing witnesses this 25 3rd day of May 1915.

GEORGE SABINI.
